UNITED STATES PATENT OFFICE

146,954

DESIGN FOR A RADIO CABINET OR THE LIKE

Donal G. Erskine, Baltimore County, Md., assignor
to Bendix Aviation Corporation, Towson, Md.,
a corporation of Delaware

Application March 11, 1946, Serial No. 127,324

Term of patent 3½ years

(Cl. D56—4)

To all whom it may concern:

Be it known that I, Donal G. Erskine, a citizen of the United States, residing in Maryland, in the county of Baltimore, have invented a new, original, and ornamental Design for a Radio Cabinet or the like, of which the following is a specification, reference being had to the accompanying drawings, forming a part thereof.

In the drawings:

Figure 1 is a perspective view of a radio cabinet or the like showing my new design;

Figure 2 is a top view thereof;

Figure 3 is an end view thereof;

What is claimed is:

The ornamental design for a radio cabinet or the like, as shown.

DONAL G. ERSKINE.
